GAME

William E. Spriggs, Des Moines, Iowa

Application March 5, 1934, Serial No. 714,156

1 Claim. (Cl. 273—107)

This invention relates to games and has for the primary object, the provision of a game apparatus for the playing of miniature horseshoes, wherein the game pieces represent horseshoes and are propelled mechanically from one goal to another so that skill and chance on the part of the players will be employed to afford maximum amusement for the players.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a game apparatus constructed in accordance with my invention.

Figure 2 is a top plan view illustrating the same.

Figure 3 is a transverse sectional view illustrating the device.

Figure 4 is a perspective view illustrating one of the game pieces.

Referring in detail to the drawing, the numeral 1 indicates a platform, the surface of which provides a playing field and arranged adjacent each end of the platform are goals 2 partially surrounded by upstanding side and end walls 3 and 4, forming a part of the platform. Arranged centrally of the goals 2 are pins 5 suitably secured to the platform. Game pieces 6 are projected from one field to the other and the purpose of the game is to encircle the pins by the game pieces or the game piece coming the closest to the pin counts over the other game pieces during each projection of the game pieces. The game differs from the ordinary playing of horseshoes in that the game pieces are mechanically propelled from one field to the other by projectors 7 instead of being manually pitched. Each game piece is of substantially annular shape with a portion removed, as shown in Figure 4.

The general outline of the game piece somewhat resembles a horseshoe.

Each projector 7 is of the same construction as well as its mounting to the platform and reference to one specifically is thought sufficient to both.

Upstanding arms 8 are secured to an end wall 4 and have pivoted thereto a body 9 which carries an extension or guide 10. The body 9 is provided with a bore slidably supporting a rod 10 11, one end of which carries a head 12 and the other end a handle or finger piece 13. The head 12 slides upon the extension 10 and includes angularly related portions, as shown in Figure 1, providing a seat for a game piece. Coil springs 15 14 are connected to the body and to the finger piece 13 and are tensioned by a pull on the finger piece 13 and when the latter is released the head 12 is propelled away from the body by said springs so as to project or throw the game piece on the head to the goal located at the opposite end of the platform from the projector which is under operation.

The projectors 7 being pivotally mounted to the platform permit the players to vary the inclination of said projectors for the purpose of varying the flight of the game piece from the projector to the goal or pin and thereby add to the playing of the game skill on the part of the player combined with chance.

Having described the invention, I claim:

A game apparatus comprising a pivotally mounted body having a reduced flattened portion forming an extension, said body having a bore, a rod slidable in the bore with one end movable over the extension, a finger piece secured to the other end of the rod, a game element engaging head secured to the rod and having angularly related portions with one portion slidable on the extension, and coil springs connected to the finger piece and to the body, said body having grooves for the springs to rest in.

WILLIAM E. SPRIGGS.
